Hermann Strauss and Robert Gardel,
New York, N. Y.

Application March 30, 1945, Serial No. 118,789

Term of patent 3½ years

(CL. D45—19)

To all whom it may concern:

Be it known that we, Hermann Strauss, a citizen of the United States of America, residing at New York city, in the county of New York and State of New York, and Robert Gardel, a citizen of the United States, residing at New York city, in the county and State of New York, have invented a new, original, and ornamental Design for a Brooch Pin, of which the following is a specification, reference being had to the accompanying drawing, forming part thereof.

In the accompanying drawing,
Fig. 1 is a front elevational view of a brooch pin showing our new design, and
Fig. 2 is an edge view of Fig. 1.

We claim:

The ornamental design for a brooch pin as shown.

HERMANN STRAUSS.
ROBERT GARDEL.
